FUEL SUPPLY SYSTEM

Philip Lane Scott, Chicago, Ill., assignor to Super Diesel Tractor Corporation, La Porte, Ind., a corporation of New York

Refiled for abandoned application Serial No. 489,749, October 20, 1930. This application March 13, 1933, Serial No. 660,526

27 Claims. (Cl. 103—152)

This invention relates to a fluid supply and pumping system. This application is a substitute for my application Serial No. 489,749, filed October 20, 1930. In one embodiment it has for 5 one object to provide means for pumping fluid and to provide means for actuating the fuel pump without the use of a mechanical linkage.

Another object is to provide in connection with 10 a fuel pump a hydraulic means for actuating the same.

Another object is to provide a fuel pump capable of discharging fuel at extremely high pressures. A still further object is to provide a 15 fluid pump capable of discharging relatively small quantities of fluid at high pressures and at great speed.

Other objects will appear from time to time in the specification and claims.

My invention is illustrated more or less diagrammatically in the accompanying drawing, 20 wherein—

Figure 1 is a section through the fuel supply system;

Figure 2 is a transverse detailed cross section 25 taken at line 2—2 of Figure 1.

Like characters illustrate like parts throughout the specification and drawing.

A is a base of any suitable sort to which the 30 actuator may be fastened. It might, for example, be a portion of an engine with which the actuator is designed to operate to furnish fuel.

B is a portion of the actuator base which may 35 be fastened to the support A by screws B¹ or by any other suitable means. The base B has an upwardly projecting hollow portion B² which is provided with a laterally extending flange B³. An actuator housing B⁴ is provided with an enlargement B⁵, having a flange B⁶ which may be placed 40 in contact with the flange B³ and fastened to it by screws B⁷ or by any other suitable means.

The member B⁴ is provided with a bore B⁸ and is preferably provided with an enlarged head portion B⁹. At its upper end the bore B⁸ is enlarged and interiorly threaded as at B¹⁰. The head portion B⁹ of the actuator housing is provided 45 with an inlet and outlet passage B¹¹ which may be enlarged and interiorly threaded as at B¹². The passage B¹¹ communicates with a passage B¹³ which leads to an annular passage or enlargement B¹⁴ in communication with and surrounding the bore B⁸. To the annular passage B¹⁴ a passage B¹⁵ leads from a passage B¹⁶, which 50 communicates with an enlargement within which a valve cage B¹⁷ is positioned. The enlargement 55 terminates at its outer end in a tapered threaded

portion B¹⁸. From the valve cage B¹⁷ a passage B¹⁹ leads to the upper end of the bore B⁸. B²⁰ is a ball check valve positioned within the intake line and adapted to be opened by suction within the actuator and seated by pressure within the actuator and by the spring shown. B²¹ is a by-pass passage leading from the upper end of the actuator bore B⁸ to a passage B²² which leads into the passage B¹¹. The by-pass valve B²³ is adapted to be seated in the passage B²¹. It is 10 provided with a threaded portion B²⁴ and a lever arm B²⁵, to which a link or connection B²⁶ may be fastened.

C is a plug seated in and closing the passage B¹⁵. C¹ is a plunger or piston mounted and 15 adapted to move within the bore B⁸ of the actuator. At its upper end it is provided with a perforation or hollowed out portion C². C³ is a perforation or cut away portion preferably adjacent the upper end of the piston C¹ and communicating with the perforation or bore C². At its lower end the piston C¹ carries the enlargement C⁴. C⁵ is a spring bearing at one end upon the housing B⁴ and at the other end upon the enlargement C⁴. C⁶ is a shaft driven in phase 20 with an engine to which the system is applied, and carrying a cam C⁷. The cam contacts the enlargement C⁴ and moves the piston during its rotation.

D is a connection seated in the passage B¹¹, 25 serving to connect the by-pass or supply conduit D¹ to the cylinder and to a supply tank, not shown.

E is a connection positioned in the passage B¹⁰ and serving to connect a supply conduit E¹ to 30 the pump cylinder. At its other end the conduit E¹ is connected to an injector unit by a connection E² which is seated in a seating or connecting portion E³, which is itself positioned upon the injector unit.

The injector unit includes an actuating tube F, which may or may not be made with enlarged ends F¹, F². The tube F is preferably of oval cross section, as indicated in Figure 2, and the enlarged ends may be rounded. The rounded 40 ends, while not essential, are usually simpler for connection to the other parts with which the tube is associated. The end F¹ is preferably mounted upon a reduced part F³ of a housing member F⁴. This member is hollow, as shown, and the tube 45 may be welded or otherwise secured upon its reduced portion F³. At its outer end the member F⁴ may be interiorly threaded as at F⁶. At its opposite end the portion F² of the tube F is fastened within a housing part F⁵. This part is in- 50 55

teriorly threaded as at F^7 to receive the correspondingly threaded portion of the actuating tube and is provided with a reduced extension F^8 which may be interiorly tapered as at F^9 and 5 exteriorly threaded as at F^{10} .

Within the tube F is mounted a second or pump tube G . This tube is preferably more or less oval in cross section as indicated particularly in Figure 2, and may be positioned so that its major 10 axis corresponds generally with the minor axis of the actuating tube F . For convenience in attachment and connection the tube G may be rounded at its ends as at G^1, G^2 . The end G^1 is positioned within and secured to the member F^4 . 15 The end G^2 is positioned within and secured to the extension F^8 of the member F^4 . For convenience the ends G^1, G^2 may be flared outwardly as indicated in Figure 1. Both of the tubes F and G may be fastened to their supporting parts 20 in any suitable manner. In the drawing they are indicated as being welded or screwed into place or both. Either of these methods of attachment may be used separately or together or any other suitable means may be used. G^3, G^4 are compression members positioned within the actuating tube F as indicated in detail in Figure 2, and having their outer ends generally curved as at G^4 and bearing against the inner walls of the actuating tube. Their inner ends 25 are more nearly flat as at G^3 and are positioned to bear against the relatively flattened sides of the pump tube G .

H is an inlet valve housing exteriorly threaded as at H^1 and screwed into place in the member F^4 engaging the threads F^5 . It is provided with an interior bore or hollow H^2 , to which a passage H^3 leads. The passage H^3 is positioned preferably in a reduced exteriorly threaded extension H^4 , to which a supply pipe or conduit H^5 leads. 30 40 This conduit is held in position on the extension H^4 by a member H^6 . Within the portion H^2 of the valve housing H is positioned a valve member H^7 , which preferably has the enlarged end H^8 , which is adapted to be seated in a valve seat H^9 formed 45 on the inner end of the valve housing H . A spring H^{10} tends normally to hold the valve seated.

Positioned on the exteriorly threaded portion F^8 and engaging the threaded part F^{10} is an injection valve housing I . This member is provided with a hollow exteriorly threaded extension I^1 and a partition portion I^2 may partially close the passage through the housing member I and the extension I^1 . This partition member is provided with a perforation I^3 . Positioned within 50 55 the extension I^1 is a cage I^4 carrying a needle point or valve closing member I^5 . The cage portion I^4 is provided with an extended and preferably annular portion I^6 against which a valve disc I^7 is positioned. This disc may be formed of 60 laminations as shown, or might be made of a single member. It is provided with a perforation I^8 and may have a removable seat plug portion I^9 , seated in the perforation I^8 and adapted to receive the needle point I^5 . I^{10} is a retaining 65 cap member threaded upon the extension I^1 , engaging and supporting the valve disc and serving to hold the member I^4 in position. This cap thus holds the entire injection valve assembly in place.

It will be realized that whereas I have here- 70 with shown and described a practical operative device, nevertheless many changes might be made in the size, shape, number and disposition of parts without departing from the spirit of my invention and I wish, therefore, that my showing be taken as in a sense diagrammatic. The com-

pression members G^3, G^4 might be omitted. If this were done a simple hydraulic drive would result, without any differential action.

The use and operation of my invention are as follows:

The actuator system is filled with liquid. Normally this may be oil of some sort although any suitable liquid may be used. The cylinder is full, the passages about the cylinder are full, the conduit E^1 is full and, in other words, the entire 10 enclosed space of the actuator system is full of liquid and the liquid column surrounds the pump tube G within the actuating tube F . To illustrate one form of the operation of the device, it will be assumed that the system as a whole is mounted with an internal-combustion engine and is 15 designed to furnish fuel to such an engine. The actuator unit may be mounted at any suitable part on the engine or in some cases on the vehicle upon which the engine is mounted. The injector or pump unit is mounted so that it will discharge fuel into an engine cylinder. The shaft C^6 is driven in phase with the engine. Assuming now that the plunger or piston C^1 is at the lower limit of its movement, its upper end is below the 20 annular portion B^{14} and thus the passages B^{13} and B^{15} are uncovered. As the shaft C^6 rotates the cam C^7 is moved so as to force the piston C^1 upward. As soon as it has moved upward a sufficient amount to pass beyond the annulus B^{14} , 25 the passages B^{13} and B^{15} are closed and if the valve B^{23} is fully seated there is no outlet for the fluid and there thus remains a solid fluid column extending from the top of the piston C^1 to the pump tube G . As the movement of the cam 30 continues, the piston is forced further upward. The liquid column is forced upward and the fluid which is for all practical purposes incompressible, is forced into the actuating tube F and tends to move it so as to increase its minor axis. 35 When this takes place its major axis is reduced and the compression blocks G^3 are forced against the pump tube G and bearing against its relatively flat sides force them towards each other, thus reducing the volume of the tube G and increasing the pressure within it. As pressure is thus developed within the pump tube G , the valve H^8 is held firmly on its seat and when the pressure increases sufficiently the yielding portion of the injection valve, normally the disc I^7 , 40 45 is forced outwardly. The amount of movement of the disc I^7 is ordinarily minute and not sufficient to move the disc or the seat portion of the disc more than minutely away from the needle, the point of which still penetrates within 50 the opening in the disc. A minute atomizing orifice is thus formed between the needle and the edges of the perforation or opening through the disc and fuel is discharged through this opening.

As the movement of the piston C^1 still continues upwardly, the opening or perforation C^3 which communicates with the hollow portion C^2 of the piston, comes into register with the annulus B^{14} and fluid may then escape through C^2, C^3 and into the annulus B^{14} . Thus during a portion of the movement of the piston, an escape is provided for the fluid above the piston, pressure is relieved, the actuating tube moves to its original position, the pump tube G is permitted to regain its original position, pressure within 70 the tube G is reduced, the valve disc resumes its original position, closing the discharge opening and terminating discharge from the valve. The pump tube G expands of its own elasticity sufficiently to create suction within itself, which 75

inseats the valve H⁸ and fuel is thus drawn into the pump tube ready for the next discharge, or injection stroke.

In the operation above described, it is stated that the valve B²³ is seated and thus no liquid can escape through the passage B²¹ past the valve B²³. This is the condition which would prevail under full load. Under less than full load, the valve B²³ is sufficiently open to permit some liquid to pass and thus to be by-passed and, therefore, the amount of liquid effective for compressing the pump tube G is reduced. The amount of movement of that tube and correspondingly the amount of liquid discharged from the pump tube is reduced. Preferably the member B²⁶ is connected to the engine control mechanism so that its movement is controlled in relation to the movement of the engine controlling mechanism.

The conventional mechanically driven pumps and mechanically operated valves have been largely incapable of rapid motion under heavy load, due to the mere size, shape and weight of parts, superimposed as resistances upon the oil pressures to be developed. A successful injection system for an engine to operate at, say 2000 R. P. M. on a two-stroke cycle engine will require 2000 pulsations in an oil column accompanied by delivery of some fuel at each pulsation. The pressure may be built up from zero to a high pressure, say 5000 pounds or above, per square inch for each pulsation. The quantity of fuel delivered is relatively a very small amount in each pulsation but it must be completely ejected in about .001 of a second and not only must complete ejection take place in this time but the pressure must rise to a maximum almost at once, perhaps as quickly as .0001 of a second. The type of pump of this application makes possible this extremely rapid building up of very high pressures in very small fractions of a second, while the plunger pumps fail at far lower speeds and pressures.

The action of the pump of this application may be likened to the building up of electric pressures in an electric ignition system. In such system electric pressure must be built up from zero to 10,000 volts in an extremely minute fraction of a second. The break down of the dielectric between the electrodes occurs when the predetermined voltage is reached, just as the flexible wall of my atomizing nozzle suddenly yields when a predetermined pressure is reached. The electric spark then discharges over an appreciable time interval just as the oil is discharged over an appreciable but very short time interval. A design which is to reduce the inertia forces substantially must have more regard for the acceleration of the parts than for the mere reduction of weight, since the inertia force is proportional to the square of the speed and only directly to the weight. If the length of the stroke or the distance through which the parts may be moved can then be very materially reduced, the inertia forces will be reduced as the squares of the speeds. Simultaneously with this reduction in length of travel of the moving parts there is also an opportunity to reduce the weight of the parts, which then reduces the inertia force in direct proportion. The total reduction so obtained may prove a very substantial figure, for example, considering the requirements of a 50 R. P. cylinder and a speed of 2000 R. P. M., the convenient size of the plunger for the conventional plunger pump would be $\frac{1}{8}$ of an inch in

diameter by $\frac{1}{8}$ stroke. The moving parts associated with this plunger may weigh well over 1 pound, since this plunger must carry a load of 550 pounds to develop a pressure of 5000 pounds per square inch upon the fuel. If the length of travel of the moving parts could be reduced from $\frac{1}{8}$ of an inch to .015 inch, the inertia will be reduced to 1.3 per cent of the preceding value. If a flexible wall weighing an ounce or less is substituted for a plunger and associated slider and roller, the weight of the parts may be cut to 6 or 7 per cent. The total reduction is such that the inertia forces will then be reduced to .09 per cent of their former figure. 15

In the invention herewith described, the difficult problem of reducing inertia forces to a point where a definite plus value of force available to produce pressure is achieved is met by reducing the travel of the elements actually producing the pressure on the fuel to an extremely minute amount or distance. These elements are, in the form shown, the fuel containing tube G (see Fig. 2) and the spacer pieces G³ which transmit the compressive force from the tube 25 F to the tube G.

As metallic members these elements have substantial weight but their travel is very minute, normally being approximately .005 inch. The result of this is that the negative inertia of the 30 parts available against the driving force is so slight as to be for practical purposes substantially negligible.

When these figures are considered in connection with the formula generally utilized for calculating the inertia force necessary to move a given part a given distance in a given time, the important and vital relationship between the weight of the part and the distance it is to be moved and the bearing these factors have on the 40 actual force necessary to be provided in a given case, is at once apparent. Thus,

$$F = \frac{WS}{1609 \times T^2}$$

wherein W is the weight of the part in pounds, S is the distance the part is moved in feet, and T is the time in seconds during which the part is moved. By utilizing a pumping chamber including a deformable metal wall, constrained to a 50 relatively minute range of movement, such as is contemplated by the present invention, the numerator of the foregoing equation may be materially reduced in comparison with the figures 55 obtaining in usual design practice. This invention comprehends a pumping chamber having a movable or deformable wall, the weight of which is relatively negligible and may be of the order of one ounce, more or less, and having a range of movement of the order of .005, but these figures 60 are merely representative and are cited for the purpose of providing comparison with values obtaining in a pump made in accordance with this invention and similar values in pumps made in accordance with prior art practice. It is well 65 within the range of possibility to make a pump in accordance with the teachings of this invention which will deliver fuel under pressure of five thousand pounds per square inch with the pump operating at two thousand strokes per 70 minute, wherein the forces necessary to overcome inertia of the moving parts are relatively small in comparison with the forces necessary to sustain hydrostatic load on the pump, and with the pump operating at substantially one thousand 75

strokes per minute and developing pressures of five hundred to one thousand pounds per square inch, the forces necessary to overcome the inertia of the moving parts may be kept well below the forces necessary to overcome the hydrostatic load on the pump.

I claim:

1. In a hydraulically driven pump, a hollow actuating member and a hollow pumping member, inlet and outlet means for said pumping member, compression parts positioned to be moved by movement of said actuating member and to move said pumping tube, and means for filling said actuating member with fluid and for 10 acting upon said member hydraulically to cause the same to change its shape and volume and to move the compression members to act upon the pumping member to change its shape and volume.
  2. In a differential hydraulically driven pump, a hollow flexible actuating member and a hollow flexible pumping member, inlet and outlet means for said pumping member, compression parts positioned to be moved by movement of said actuating member and to move said pumping tube, and means for filling said actuating member with fluid and for acting upon said member hydraulically to cause the same to change its shape and volume and to move the compression members to act upon the pumping member to change its shape and volume.
  3. In a hydraulically driven pump, a hollow actuating member and a hollow pumping member, inlet and outlet means for said pumping member, compression parts positioned to be moved by movement of said actuating member and to move said pumping tube, and means for filling said actuating member with fluid and for acting upon said member hydraulically to cause the same to change its shape and volume and to move the compression members to act upon the pumping member to change its shape and volume, the actuating member being capable of returning of itself to its original form when free to do so.
  4. In a hydraulically driven pump, a hollow actuating member and a hollow pumping member, inlet and outlet means for said pumping member, compression parts positioned to be moved by movement of said actuating member and to move said pumping tube, and means for filling said actuating member with fluid and for acting upon said member hydraulically to cause the same to change its shape and volume and to move the compression members to act upon the pumping member to change its shape and volume, the pumping member being capable of returning of itself to its original form when free to do so.
  5. In a hydraulically driven pump, a hollow actuating member and a hollow pumping member, inlet and outlet means for said pumping member, compression parts positioned to be moved by movement of said actuating member and to move said pumping tube, and means for filling said actuating member with fluid and for acting upon said member hydraulically to cause the same to change its shape and volume and to move the compression members to act upon the pumping member to change its shape and volume, the actuating member and the pumping member each being capable of returning of itself to its original form when free to do so.
  6. In a hydraulically driven pump, a hollow flexible actuating tubular member and a hollow flexible pumping member, inlet and outlet means for said pumping member, compression parts

positioned to be moved by movement of said actuating member and to move said pumping tube, and means for filling said actuating member with fluid and for acting upon said member hydraulically to cause the same to change shape and volume, and to move the compressing members to act upon the pumping member to change its shape and volume.

7. In a hydraulically driven pump, a hollow actuating member and a hollow tubular pumping member, inlet and outlet means for said pumping member, compression parts positioned to move by movement of said actuating member and to move said pumping tube, and means for filling said actuating member with fluid and acting upon said member hydraulically to cause the same to change its shape and volume, and move the compression members to act upon the pumping member, to change its shape and volume.

8. In a hydraulically driven pump, a hollow actuating flexible tubular member and a hollow flexible tubular pumping member, inlet and outlet means for said pumping member, compressible parts positioned to be moved by movement of said actuating member and to move said pumping tube, and means for filling said actuating member with fluid and for acting upon said member hydraulically to cause the same to change its shape and volume and to move the compressible members to act upon the pumping member to change its shape and volume.

9. In a hydraulically driven pump, a hollow actuating tubular member and a hollow pumping member, inlet and outlet means for said pumping member, compression parts positioned to be moved by movement of said actuating member and move said pumping tube, and means for filling said actuating member with fluid and for acting upon said member hydraulically to cause the same to change its shape and volume, and to move the compression members to act upon the pumping member to change its shape and volume, the actuating member being capable of returning itself to its original form when free to do so.

10. In a hydraulically driven pump, a hollow actuating member and a hollow tubular pumping member, inlet and outlet means for said pumping member, compression parts positioned to be moved by movement of said actuating member and move said pumping tube, and means for filling said actuating member with fluid and for actuating upon said member hydraulically to cause the same to change its shape and volume, and to move the compression members to act upon the pumping member to change its shape and volume, the pumping member being capable of returning itself to its original form when free to do so.

11. In a hydraulically driven pump, a hollow actuating tubular member and a hollow tubular pumping member, inlet and outlet means for said pumping member, compression parts positioned to be moved by movement of said actuating member and to move said pumping tube, and means for filling said actuating member with fluid for acting upon said member hydraulically to cause the same to change its shape and volume and to move the compression members to upon the pumping member to change its shape and volume, the actuating member and the pumping member each being capable of returning itself to its original form when free to do so.

12. In a hydraulically driven pump, a hollow actuating member and a hollow pumping member, inlet and outlet means for said pumping member

compression parts positioned to be moved by movement of said actuating member and to move said pumping tube, said parts being within the actuating member, and means for filling said actuating member with fluid and for acting upon said member hydraulically to cause the same to change its shape and volume, and to move the compression members to act upon the pumping member to change its shape and volume.

13. In a hydraulically driven pump, a hollow actuating member and a hollow pumping member, within said actuating member, inlet and outlet means for said pumping member, compression parts positioned within said actuating member to be moved by movement of said actuating member and to move said pumping tube, and means for filling said actuating member with fluid and for acting upon said member hydraulically to cause the same to change its shape and volume and to move the compression members to act upon the pumping member to change its shape and volume.

14. In a hydraulically driven pump, a hollow actuating member and a hollow pumping member, within said actuating member, inlet and outlet means for said pumping member, compression parts positioned to be moved by movement of said actuating member and to move said pumping tube, said parts being within the actuating member, and means for filling said actuating member with fluid and for acting upon said member hydraulically to cause the same to change its shape and volume, and to move the compression members to act upon the pumping member, to change its shape and volume.

15. In a differential hydraulically driven pump, a hollow actuating member and a hollow pumping member within said actuating member, inlet and outlet means for said pumping member, compression parts positioned to be moved by movement of said actuating member and to move said pumping tube, said parts being within the actuating member, and means for filling said actuating member with fluid and for acting upon said member hydraulically to cause the same to change its shape and volume, and to move the compression members to act upon the pumping member, to change its shape and volume.

16. In a hydraulically driven pump, a hollow actuating member and a hollow pumping member within said actuating member, inlet and outlet means for said pumping member, compression parts positioned to be moved by movement of said actuating member and to move said pumping tube, said parts being within the actuating member, and means for filling said actuating member with fluid and for acting upon said member hydraulically to cause the same to change its shape and volume, and to move the compression members to act upon the pumping member to change its shape and volume, the actuating member and the pumping member each being capable of returning of itself to its original form when free to do so.

17. In a hydraulically driven pump, a hollow actuating tubular member and a hollow tubular pumping member, within said actuating member, inlet and outlet means for said pumping member, compression parts positioned within said actuating member to be moved by movement of said actuating member and to move said pumping tube, and means for filling said actuating member with fluid and for acting upon said member hydraulically to cause the same to change its shape and volume, and to move the compression members

to act upon the pumping member to change its shape and volume.

18. In a hydraulically driven pump, a hollow actuating tubular member and a hollow tubular pumping member, within said actuating member, inlet and outlet means for said pumping member, compression parts positioned to be moved by movement of said actuating member and to move said pumping tube, said parts being within the actuating member, and means for filling said actuating member with fluid and for acting upon said member hydraulically to cause the same to change its shape and volume, and to move the compression members to act upon the pumping member to change its shape and volume. 15

19. In a differential hydraulically driven pump, a hollow actuating tubular member and a hollow tubular pumping member within said actuating member, inlet and outlet means for said pumping member, compression parts positioned to be moved by movement of said actuating member and to move said pumping tube, said parts being within the actuating member, and means for filling said actuating member with fluid and for acting upon said member hydraulically to cause the same to change its shape and volume, and to move the compression members to act upon the pumping member to change its shape and volume. 20

20. In a differential hydraulically driven pump, a hollow actuating tubular member and a hollow tubular pumping member, within said actuating member, inlet and outlet means for said pumping member, compression parts positioned to be moved by movement of said actuating member and to move said pumping tube, said parts being within the actuating member, and means for filling said actuating member with fluid and for acting upon said member hydraulically to cause the same to change its shape and volume, and to move the compression members to act upon the pumping member to change its shape and volume. 25

21. In a fuel supplying system, a hydraulically actuated pump, comprising two tubular members, one within the other, means for supplying fluid under pressure to the space within the outer tube and means for creating pressure upon such fluid to distort the outer tube and thereby to compress the inner tube, said pressure creating means comprising a pump having a housing, a plurality of passages within the housing, a pump chamber and a piston lying within the chamber, there being passages within the piston, all of said passages forming a closed system, whereby as the piston is reciprocated the fluid within the closed system is compressed. 45

22. In a fuel supplying system, a hydraulically actuated pump, comprising two tubular members, one within the other, means for supplying fluid under pressure to the space within the outer tube and means for creating pressure upon such fluid to distort the outer tube and thereby to compress the inner tube, said pressure creating means comprising a pump having a housing, a plurality of passages within the housing, a pump chamber and a piston lying within the chamber, there being passages within the piston, all of said passages forming a closed system, whereby as the piston is reciprocated the fluid within the closed system is compressed, and automatic means connecting the said closed circuit with a fluid supply, whereby a substantially constant quantity 60

of fluid is automatically maintained within the closed system.

23. In a mechanism for creating intermittent high pressure in a liquid system, a vessel adapted to contain the liquid to be acted upon, means for applying pressure to the liquid within the vessel, said means including a flexible metallic member and a co-operating rigid driving member bearing against and adapted to act directly upon said flexible metallic member, the flexible member positioned to exert pressure upon the liquid containing vessel and hydraulic means for actuating said metallic flexible member, said flexible member and said rigid driving member being dimensioned and proportioned as to weight and controlled as to range of movement such that the inertia force of said members when moving at a speed of more than 2000 strokes per minute is less than the transmitted force required to produce 5000 pounds per square inch pressure upon the liquid.

24. In a mechanism for creating intermittent high pressure in a liquid system, a vessel adapted to contain the liquid to be acted upon, means for applying pressure to the liquid within the vessel, said means including a flexible member and a cooperating mechanical driving means in contact with said flexible member, the flexible member positioned to exert pressure upon the liquid contained within the vessel, and hydraulic means for actuating said flexible member, said flexible member and cooperating mechanical driving means being dimensioned and proportioned as to weight and controlled as to range of movement so that the inertia force of said members when moving at a speed of more than one thousand strokes per minute, is less than the transmitted force required to produce one thousand pounds per square inch upon the liquid.

25. In a mechanism for creating intermittent high pressure in a liquid system, a vessel adapted to contain the liquid to be acted upon, means for applying pressure to the liquid within the vessel, said means including a flexible member and a co-operating mechanical driving member bearing against and adapted to operate directly upon said

flexible member, the flexible member positioned to exert pressure upon the liquid contained in the vessel, and hydraulic means for actuating said flexible member, the flexible member and said mechanical driving member being dimensioned and proportioned as to weight and controlled as to range of movement so that the inertia force of said members when moving at speeds of more than one thousand strokes per minute is less than the transmitted force required to produce five hundred pounds per square inch pressure upon the liquid.

26. In a liquid fuel pump, a metallic pumpin chamber of variable volumetric capacity and including a deformable wall, a pressure chamber overlying said deformable wall, a pressure medium within said chamber, and means for creatin pulsations in said medium, rigid means for transmitting said pulsations to said deformable wall said deformable wall and said rigid means being dimensioned and proportioned as to weight and controlled as to range of movement such that the force necessary to overcome inertia thereof is less than the force necessary to overcome the hydrostatic load on said wall member.

27. In a high pressure liquid fuel pump, pumping chamber of variable volumetric capacity and including a relatively movable wall member, a pressure chamber overlying said wall member and including a relatively movable wall, a pressure medium within said pressure chamber, rigid motion transmission means operatively interposed between the movable wall of the pressure chamber and the movable wall of the pumping chamber, means for creating in said pressure chamber alternate pulsations of high and low pressure to cause movement of said wall members to periodically vary the volumetric capacity of the pumping chamber, said wall members and interposed rigid member being constrained to a range of movement with respect to their relative weight such that the force necessary to overcome the combined inertia of said elements is less than the force necessary to overcome the hydrostatic load on the movable wall of the pump.

PHILIP LANE SCOTT.
